INSTRUMENT HOLDER

Sidney H. Sherman, Chicago, Ill.

Application November 4, 1947, Serial No. 783,877

3 Claims. (Cl. 211—70)

1

The present invention relates in general to instrument holders, and has more particular reference to an inexpensive, collapsible device or stand adapted to be easily set up in operating position for supporting musical instruments, such as horn mutes, maracas, and similar musical accessories, in convenient, readily accessible position, so that the musician may pick up any supported instrument for use at any time during a musical performance and return the instrument to the stand.

An important object of the present invention is to provide an inexpensive instrument support of exceedingly simple, yet rugged construction, readily attachable, as on a music mounting rack, to provide means for separately supporting a number of musical accessories, such as horn mutes, maracas, and the like; a further object being to provide a support device of the character mentioned, which is readily collapsible to compact folded condition occupying minimum space for storage or transportation, and which is as readily opened to and locked in expanded operating position.

Another important object is to provide a collapsible support device comprising a minimum number of relatively simple and inexpensive parts; a further object being to provide a device comprising a sheet metal mounting arm and a plurality of instrument supporting arms pivotally mounted for fanning movement about a common mounting axis on said mounting arm, and easily operable clamp means for securing said instrument supporting arms in relatively fanned or in relatively folded position.

Another object is to form the instrument supporting arms from inexpensive wire stock by providing an instrument supporting loop at one end of a wire stock piece and a pivot loop at the other end of the piece; a further object being to pivotally mount the several instrument supporting arms by assembling the pivot loops thereof upon a threaded clamping stem on the mounting arm, and provided with a threaded clamping nut for securing the instrument support arms in folded or fanned position on the mounting arm.

Another important object is to provide a plurality of supporting arms of different length, whereby the supporting loops thereof are carried at different distances from the member on which the arms are mounted, thereby enabling said loops to be disposed in circumferentially offset or staggered position when the device is in open position; another object being to provide arms having support loops of unlike dimension to accommodate musical accessories of different size.

2

The foregoing and numerous other important objects, advantages, and inherent functions of the invention will become apparent as the same is more fully understood from the following description, which, taken in connection with the accompanying drawings, discloses a preferred embodiment of the invention.

Referring to the drawings:

Fig. 1 is a perspective view of a device embodying the present invention and shown in operative instrument supporting position;

Fig. 2 is a sectional view taken longitudinally through the device shown in Fig. 1 when the same is in folded or collapsed position;

Fig. 3 is a top view of the device as shown in Fig. 2; and

Fig. 4 is a sectional view taken substantially along the line 4—4 in Fig. 2.

To illustrate the invention, the drawings show 20 an instrument support 11 comprising a strip of sheet metal 12 forming a mounting member, said strip being twisted, as at 13, intermediate the ends thereof to dispose one end of the strip in a plane substantially at right angles with respect 25 to the opposite end of the strip. One end of the strip is bent to provide a loop or hook 14 adapted to be applied detachably around any convenient support member, such as a rod or post 15, which may, for example, constitute the post of a music 30 rack, on which it may be desired to anchor the device 11, the terminal portions of the hook 14 being provided with a re-bent tip portion 16 carrying a thumb screw 17 adapted to be tightened in order to secure the hook 14 upon the member 15, and to be loosened in order to release the member 15 and allow the support device 11 to be dismounted therefrom.

The strip 12, at its end remote from the hook 14, carries a threaded stem 18 fixed thereto in 40 position extending at right angles with respect to the plane of said end of the strip. The threaded member 18, thus, extends in a direction substantially parallel with respect to the support member 15 on which the device may be mounted. The member 18 preferably comprises a standard bolt extending through an opening formed at the end of the member 12, with the head of the bolt welded or otherwise secured in place on the member 12. The member 18 serves 45 to mount several instrument supporting arms 19 and 20 on the carrying member 12.

The arms 19 and 20 may conveniently be formed of wire stock, each arm being formed from a suitable length of wire by bending the 50 same to form a mounting loop 21 at one end

thereof. The mounting loops 21 of the several arms are preferably of like size and adapted to slidably receive the stem of the bolt 18, whereby all of the support arms 19 and 20 may be assembled on the stem and secured in place thereon, as by means of a holding and clamping nut 22, adapted for manual operation on the stem 18 to clamp the mounting loop portions of the several arms together on the member 12, or to release the same for relative angular fanning movement about the axis of the stem 18.

Each of the arms 19 and 20, at the end thereof of remote from the mounting loop 21, is preferably bent to provide a support loop 23, the terminal end of the constituent wire being welded, soldered, or otherwise attached to the body of the wire, as at 24, to rigidify and strengthen the loop, or said terminal end may be left unattached, if desired.

The loops 23 of the several arms may be of unlike size. As shown, the loops of the arms 19 preferably comprise loops of relatively large diameter, while those of the arms 20 may be of lesser diameter, the arm length between the mounting and supporting loops 21 and 23 being greater in the members 20 than in the members 19, so that when fanned in the manner shown in Fig. 1, the loops 23 of adjacent arms may be disposed at different distances with respect to the support stem 18, thereby circumferentially staggering the loops to facilitate the application and removal of musical accessories. While the invention is not necessarily so restricted, I prefer to provide six supporting arms, as shown, and to make three of said arms, such as the arms 19, with relatively large loops 23 of identical size and configuration, the remaining arms 20 having loops 23 of relatively smaller size, said loops 23 of the arms 20 being all of the same size and configuration.

I prefer, also, to mount the arms 19, having the loops of relatively large size, on the stem 18 immediately next to the member 12, and to form the loops 23 of said arms 19 of such a size as to register with the twisted portion 13 of the support member 12, so that when in collapsed position, as shown in Fig. 3, the twisted hook carrying portion of the member 12 may be received within the loops 23 of the arms 19, to thereby minimize the over-all thickness of the device when in collapsed position.

In this connection, it will be noted that the loops 23 of the arms 19 substantially encircle and enclose the hooked portion 14 of the support arm, including the thumb screw 17, whereby said thumb screw, when the device is in collapsed position, is guarded by the loops 23 of the arms 19 against becoming snagged. Accordingly, when the device is in collapsed position, it may be readily carried about, as in the pocket of the owner. It will be noted, also, that the arms 20, when the device is in collapsed position, may extend diametrically with respect to the loops 23 of the arms 19, whereby said arms 20 and portions of the loops 23 thereof, will underlie the loops 23 of the arms 19 and close the same below the hook portion 14 of the mounting arm 12, thereby aiding in enclosing said hook and attached thumb screw within the loops 23 of the arms 19 when the device is in collapsed position. When so arranged, the relatively longer arms 20 and the loops 23 thereof do not materially increase the folded bulk of the device. The arms 19 and 20, of course, may be secured in relatively folded position merely by tightening the

thumb nut 22, whereby the device in folded position may be constituted as a neat, compact package occupying minimum space for convenient transportation or storage.

By loosening the thumb nut 22, the arms 19 and 20 may be relatively fanned to open position, as shown in Fig. 1, or to any other preferred relatively open position of the arms 19 and 20, on the support arm 12; and the arms 19 and 20 may be locked in open position on the support arm 12 merely by tightening down the thumb nut 22. When so tightened, the arms 19 and 20 are rigidly clamped against movement, so that the stand provides a rigid, solid support which may be anchored on any convenient base, such as is afforded by the stem or post of a music rack.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. A compactly foldable support stand comprising a sheet metal strip forming a mounting bar, said strip having a curled and offset portion forming an attaching clamp at one end of said bar, means forming a pivot on said bar in spaced relation with respect to said clamp, and a plurality of support members of like size and configuration and adjustably supported on said pivot for relative angular movement thereon, with respect to each other and said bar, whereby the stand may be adjusted to open position in which the members and bar extend each in a different direction radially of the pin, said members comprising mounting portions connected on said pivot, and loop portions spaced from said mounting portions a distance such that, when said members are disposed in folded relationship, on said pivot, in alignment with said bar and each other, the aligned loop portions of said members form an enclosure within which said curled and offset clamp forming portion is received and housed, to thereby present the support stand in compact conveniently pocketable condition when in folded relationship.

2. A compactly foldable support stand comprising a sheet metal strip forming a mounting bar, said strip having a curled and offset portion forming an attaching clamp at one end of said bar, means forming a pivot on said bar in spaced relation with respect to said clamp, a plurality of support members of like size and configuration and adjustably supported on said pivot for relative angular movement thereon, with respect to each other and said bar, whereby the stand may be adjusted to open position in which the members and bar extend each in a different direction radially of the pin, said members comprising mounting portions connected on said pivot, and loop portions spaced from said mounting portions a distance such that, when said members are disposed in folded relationship, on said pivot, in alignment with said bar and each other, the aligned loop portions of said members form an enclosure within which said curled and offset clamp forming portion is received and housed, to thereby present the support stand in compact conveniently pocketable condition when in folded relationship, and manually operable clamp means

for securing said members and bar in folded and in angularly adjusted position on said pivot.

3. A compactly foldable support stand comprising a sheet metal strip forming a mounting bar, said strip having a curled and offset portion forming an attaching clamp at one end of said bar, means forming a pivot on said bar in spaced relation with respect to said clamp, a plurality of support members of like size and configuration and adjustably supported on said pivot for relative angular movement thereon, with respect to each other and said bar, whereby the stand may be adjusted to open position in which the members and bar extend each in a different direction radially of the pin, said members comprising mounting portions connected on said pivot, and loop portions spaced from said mounting portions a distance such that, when said members are disposed in folded relationship, on said pivot, in alignment with said bar and each other, the aligned loop portions of said members form an enclosure within which said curled and offset clamp forming portion is received and housed, to

thereby present the support stand in compact conveniently pocketable condition when in folded relationship, and additional support members angularly adjustable on said pivot and having portions spaced from said pivot a distance such that said portions may extend across said loop portions at an end of said enclosure to enclose said end when the stand is in folded relationship with said additional member in alignment with said plurality of support members radially of the pivot.
